 BALL AND SPRING WIRE CATAPULT
 Robert Ellis, 350 E. Plaza, Solana Beach, Calif.
 Filed July 14, 1964, Ser. No. 382,580
 5 Claims. (Cl. 124—10)

This invention relates to toys and the principal object of the invention is the provision of a cheap, simple and amusing toy for children's use from two to twelve years of age, the toy being of the upward propulsion type, from a table or floor and adaptable for inside or outside use.

Another object of the invention is to provision of means for giving to the projectile an extra impulse.

Other and further objects will appear in the specifications and be specifically pointed out in the appended claims, reference being had to the accompanying drawings exemplifying the invention, and in which:

FIG. 1 is a top view of the catapult.

FIG. 2 is a top view illustrating the means of propulsion.

FIG. 3 is a side view of FIG. 2.

FIG. 4 is a sectional view illustrating the means for imparting extra propulsive effort to the projectile.

FIG. 5 is a side view illustrating the beginning of the downward stroke.

Referring to the drawings in which like characters and numerals of reference refer to similar parts throughout the several views, the numeral 7 denotes the handle of a spring-wire catapult the other end of which handle comprises a circular loop 8, bisected at 9, thus forming two semi-circular loops 8A. The two oppositely disposed semi-circular loops 8A are therefor tensioned against each other in the direction of arrows 10 when an object larger in diameter than the circular loop 8, such as a ball 11, is inserted therebetween, as illustrated in FIG. 2. Additional lateral pressure against the opposite sides of the ball 11 is provided by the fingers F and thumb T as shown in dotted lines in FIG. 2 as the handle 7 is held in the hand, which permits squeezing the handle parts 7 together in the direction of arrows 10, thus augmenting the normal pressure of the spring handle.

The operation of this toy is as follows: the child simply lays the ball 11 onto a horizontal table or floor surface 12 and then places the circular loop 8 over the top of the ball and presses downward in the direction of arrow 13, the bisected loop sections 8A thus being caused to spread, as illustrated in FIGS. 2 and 3, the diameter of the ball being slightly greater than that of the inside of the loop 8. As the handle 7 is pressed downward still further, past the maximum diameter of the ball 11, the lateral pressure of the two oppositely disposed semi-circular loops 8A will cause the ball to be propelled upwards from the floor 12 in the direction of arrow 16 a considerable distance to the delight of the child. This action is then repeated as often as desired. It will be apparent that the height of the ascension of ball 11 from floor 12 is largely determined by the degree of lateral pressure exerted in the direction of arrows 10 by the fingers F and thumb T respectively although the lateral compressive pressure of the spring arms 7 will also suffice to catapult the ball.

To further increase the height of ascension of ball 11, a helical compression spring 14 may be employed, the spring resting on the floor 12 as shown in FIGS. 4 and 5, the circular opening at the top of the spring serving as a convenient resting place for the ball 11. As the handle 7 is pressed downwards, the loops 8A will exert pressure on top of the ball 11, this pressure first compressing the helical spring 14, the resistance of this spring being slightly less than that of the semi-loops 8A, and as the loops 8A pass the maximum diameter of the ball 11 on their down-

2

ward path, both springs will suddenly act in unison and propel the ball 11 to a greater height than if only the spring wire catapult 7 were used, as will be readily understood. The outer diameter of the helical compression spring 14 is less than the inner diameter of the loop 8 so that the loop 8 will pass over the helical spring body 14, as indicated by dotted lines 7A in FIG. 4, thus preventing the helical spring 14 from bouncing away at each performance. It will be noted that the catapult actually traps the spring 14 by clamping it against the floor 12, the bottom convolution of the spring being denoted by the numeral 15.

Many different appearing objects may be used as a projectile such as a simulation rocket 11A, see FIG. 5, which also illustrates the beginning of each downward stroke of the catapult, the helical compression spring 14 being shown in its normal expanded condition.

From the foregoing description it will be apparent that I have evolved a simple, cheap and amusing toy especially adapted for young children, consisting of only two or three parts and enjoying considerable amusement and which will last a long time, also affording competitive skill in trying to catapult the projectile to the highest point.

I claim:

- 25 1. A toy comprising a ball and a spring wire catapult means, said catapult having a looped spring handle, each projecting end of which looped spring handle terminates in a generally semi-circular end portion, said end portions being mutually oppositely disposed and forming an opening of generally circular configuration, said opening being slightly smaller in diameter than said ball so that when said end portions of said spring handle are pressed downward and forced over said ball the said ball will be projected upwardly through said circular opening afforded by the momentarily separated semi-circular ends of said spring handle.
- 30 2. A toy as in claim 1, and a helical spring adapted to be placed upright on a solid surface beneath said ball, the bottom of said ball resting within the opening of the upper loop of said helical spring.
- 35 3. A toy as in claim 1, and a helical spring adapted to be placed upright on a solid surface beneath said ball, the bottom of said ball resting within the opening of the upper loop of said spring, the said helical spring being of lesser diameter than the aforesaid opening of said catapult.
- 40 4. A toy as in claim 1, and a helical spring adapted to be placed upright on a solid surface beneath said ball, the bottom of said ball resting within the opening of the upper loop of said spring, the said helical spring being at its upper end of lesser diameter than the aforesaid opening of said catapult means, the lowermost loop of said helical spring is of equal or larger diameter than said opening of said catapult means.
- 45 5. A toy as in claim 1, and a helical spring, said helical spring being adapted to be placed upright onto a solid surface, the said ball being adapted to be placed onto the upper loop of said helical spring, said helical spring being of lesser diameter than the inner diameter of the aforesaid circular configuration of said catapult, and the compression resistance of said helical spring being of lesser resistance than that of the said spring handle at the moment it passes the maximum diameter of said ball.
